DESIGN FOR A PACKAGE SEALING MACHINE

Herbert Rosengren, Woodcliffe Lake, N. J., assignor to Pneumatic Scale Corporation, Limited, Quincy, Mass., a corporation of Massachusetts

Application March 15, 1939, Serial No. 83,586

Term of patent 14 years

To all whom it may concern:

Be it known that I, Herbert Rosengren, a citizen of the United States, residing in Woodcliffe Lake, in the county of Bergen, and State of New Jersey, have invented a new, original, and ornamental Design for a Package Sealing Machine, of which the following is a specification, reference being had to the accompanying drawing, forming part thereof.

Fig. 1 is a front perspective view of a package sealing machine showing my new design; and Fig. 2 is a rear perspective view thereof.

I claim:

The ornamental design for a package sealing machine, as shown.

HERBERT ROSENGREN.
